LIQUID DISPENSING CLOSURE CAP

Domenick P. Barravecchia, 54 Stillman Ave.,
Westerly, R.I.

Filed Mar. 6, 1959, Ser. No. 797,661

4 Claims. (Cl. 215—65)

This invention relates to closure means for liquid containers and constitutes a continuation-in-part of my co-pending application Serial No. 661,408, filed July 24, 1957, and entitled "Combined Cap, Valve and Dispensing Spout for Liquid Containers."

More specifically, the present invention relates to a closure cap for conventional beverage containing bottles having a reduced neck portion which terminates in a beaded end.

One of the primary objects of this invention is to provide a cap for conventional bottles with means for releasably securing the cap across the open end of the bottle.

Another object of this invention is to provide a closure cap of the type generally described with unique means for quickly and releasably securing the cap on the open end of the bottle or container.

This invention contemplates, as a still further object thereof, the provision of a closure cap for a bottle or container together with means for releasably securing the cap on the open end of the container, the means being non-complex in construction and assembly, inexpensive to manufacture, and durable in use.

Other and further objects and advantages of the instant invention will become more apparent from a consideration of the following specification when read in conjunction with the annexed drawing, in which:

Figure 1 is a perspective view of a closure cap constructed in accordance with this invention, the cap being illustrated as releasably connected to the open end of a bottle or container;

Figure 2 is an enlarged detail cross-sectional view of the closure cap, and of the releasable securing means, Figure 2 being taken substantially on the vertical plane of line 2—2 of Figure 1, looking in the direction of the arrows;

Figure 3 is a bottom plan view of the closure cap illustrated in Figure 1, Figure 3 being partly in section and taken substantially on the line 3—3 of Figure 2, looking in the direction of the arrows; and,

Figure 4 is an enlarged detail cross-sectional view of the closure cap with the releasable securing means moved to its inoperative position to permit the cap to be removed from the bottle or container.

Referring now more specifically to the drawing, reference numeral 10 designates, in general, a closure cap constructed in accordance with this invention and adapted for connection with a liquid container or bottle 12, the contents of which are to be dispensed. The cap 10 is seen to comprise a substantially hollow cylindrical member 14 including a side wall 16 having a depending integrally formed arcuately shaped clip 18 extending from one end thereof, and an end wall 20 extending across and closing the other end of the side wall 16. A resilient sealing element 22 formed of rubber or other similar material is disposed within the cylindrical member 14 and substantially fills the same. As is seen in Figures 2 and 4,

2

the end wall 20 and sealing element 22 have confronting abutting sides.

A discoidal member 24 having an area substantially equal to the area of the end wall 20 is rigidly secured thereto in face-to-face engagement by conventional means. The member 24 is provided with an integrally formed laterally and outwardly extending tongue 26 from which depend a pair of laterally spaced integrally formed standards 28, 30.

Reference numeral 34 denotes a substantially U-shaped lever which includes a bight 36 from the opposed ends of which project a pair of laterally spaced and substantially parallel side arms 38, 40. As is seen in Figures 2 and 4, the bight 36 is longer than the width of the side arms 38, 40, and the bight 36 terminates in an upwardly inclined flange 42 forming a second clip. From Figure 3 it is seen that the outer end of the second clip or flange 42 terminates in an arcuately shaped end 46. The lever 34 is pivotally supported on a pivot pin 48 which extends through the side arms 38, 40 and has its respective opposed ends fixedly secured to the standards 28, 30.

Reference numeral 50 designates, in general, a second lever. This lever is seen to be substantially U-shaped in configuration and includes a pair of laterally spaced and substantially parallel side walls 52, 54. The side walls 52, 54 are each provided with cam surfaces 56, 58 at their respective upper ends which continue into substantially planar extensions 60, 62. The bight 64 of the second lever 50 extends at one of its ends beyond the side walls 52, 54 to form means for manually operating the lever 50. As is seen in Figure 2, the free end 64A of the lever 64 is arcuately curved for positioning in spaced relation relative to the container 12 to provide finger space therebetween when actuating the lever 50 from its operative locked position to its unlocked or released position. The second lever 50 is pivotally mounted on a pivot pin 66 which extends through the end walls 52, 54 and has its respective ends fixedly secured to and supported on the side arms 38, 40 adjacent their respective outer ends.

The above described device 10 is designed to be used in conjunction with a conventional beverage containing bottle 12 having a reduced neck portion 68 which terminates in a beaded end 70. To utilize the device 10, reference is made specifically to Figure 4 of the drawings. In this figure the component elements of the device 10 are illustrated in their respective positions as the closure cap 10 is being connected to the open end of the bottle 12. As is shown in this figure, a portion of the bead 70 of the bottle 12 is received within the hollow cylindrical side wall 16 and abuts the adjacent side of the resilient sealing element 22. The first clip 18 is made to engage around the bead 70 after which the bight 64 is pivoted downwardly in a counterclockwise direction to cause the flange 42 to engage below the bead 70 on the diametrical opposed side of the bottle 12. As the bight 64 is rotated in the manner described, the cam surfaces 56, 58 ride against the underside of the tongue 26 and the flange or clip 42 becomes fixedly locked against the bead 70 when the planar extensions 60, 62 engage against the underside of the tongue 26.

The closure cap 10 now assumes its position relative to the bottle 12 in the manner illustrated in Figure 2.

When it is desired to remove the closure cap 10 from the bottle 12 to dispense contents therefrom, the same is accomplished through the simple expedient of rotating the bight 64 in a clockwise direction to cause the lever 34 to pivot and effect disengagement of the flange 42 from beneath the bottle bead 70.

Having described and illustrated one embodiment of this invention in detail, it will be understood that the same is offered merely by way of example, and that

this invention is to be limited only by the scope of the appended claims.

What is claimed is:

1. A closure cap for a liquid receptacle having a neck and including a beaded open end, said closure cap comprising a hollow cylindrical member having an end wall extending across one end thereof, a tongue fixedly secured to said end wall and projecting laterally therefrom, a resilient sealing element disposed within said cylindrical member and substantially filling the same, said cylindrical member adjacent the open end thereof having a depending arcuately shaped bead engaging clip formed integral therewith, a lever pivotally mounted on said tongue, said lever having a bead engaging clip at an end thereof, said last named bead engaging clip being pivotal towards and away from said bead to releasably secure said cap on said neck, and means securing said lever with said last named clip engaging said bead.

2. A closure cap for a liquid receptacle having a neck terminating in a beaded open end, said closure member comprising a substantially hollow cylindrical member having a pair of opposed open and closed ends, a substantially arcuately shaped bead engaging clip depending from said cylindrical member adjacent said open end thereof, a resilient sealing element disposed within said cylindrical member and superimposed against said closed end thereof, said resilient sealing element substantially filling said cylinder, a tongue fixedly secured to said closed end and projecting laterally therefrom, said tongue having a standard depending from each side thereof, said standards being integrally formed with said tongue and disposed in laterally spaced and substantially parallel relation, a substantially U-shaped lever having a pair of opposed side arms and a bight, means pivotally connecting said side arms with said standards, said bight having a terminal portion bent at an acute angle with respect thereto and extending toward said cylindrical member, a substantially U-shaped second lever, said second lever including a bight having a pair of laterally spaced side walls projecting therefrom, one end of said last named side walls having cam surfaces thereon which continue into planar extensions, means pivotally connecting said side walls with said side arms adjacent the outer free ends of the latter, said last named lever being pivotal to pivot said first named lever in such a direction as to cause said first named lever in such a direction as to cause said last named clip to move inwardly toward and engage

against said bead with said planar surfaces engaging against said tongue to releasably secure said closure cap on said receptacle.

3. A closure cap for a liquid receptacle having a dispensing neck terminating in a beaded end, said cap comprising a substantially hollow cylindrical member having a pair of opposed open and closed ends, said cylindrical member having a bead engaging clip depending therefrom adjacent said open end thereof, a resilient sealing element disposed within said cylindrical member and superimposed against said closed end thereof, said resilient sealing element substantially filling said cylindrical member, a tongue fixedly secured to said closed end and projecting laterally therefrom, said tongue having a standard depending from each side thereof, said standards being integrally formed with said tongue and disposed in laterally spaced and substantially parallel relation, a substantially U-shaped lever having a pair of opposed side arms and a bight, means pivotally connecting said side arms with said standards, said bight having a terminal portion bent at an acute angle with respect thereto and extending toward said cylindrical member, said terminal portion having an arcuately shaped clip at its outer end, a substantially U-shaped second lever, said second lever including a bight having a pair of laterally spaced side walls projecting therefrom, one end of each of said side walls having cam surfaces formed thereon which continue into planar extensions, means pivotally connecting said side walls with said side arms adjacent the outer free ends of the latter, said last named lever being pivotal to pivot said first named lever in such a direction as to cause said last named clip to move inwardly towards and to engage against said bead on diametrically opposed sides thereof with respect to said first clamp and with said planar surfaces engaging against said tongue to releasably secure said closure cap on said receptacle.

4. A closure cap as defined in claim 3, and said lever adjacent the free end thereof being spaced from adjacent portions of said container when said cap is releasably secured thereon.
